CLOTHES WRINGER

Edward Stroschein, Oshkosh, Wis.

Application September 7, 1937, Serial No. 162,715

4 Claims. (Cl. 62—253)

This invention pertains to clothes wringers, and more particularly to wringers employed in connection with power-driven washing machines.

The invention has primarily for its object to provide an exceedingly simple and inexpensive power-driven wringer, capable of positive pressure control and quick release.

Another object resides in the provision of a wringer having rolls normally positioned at an angle to the vertical axis of the machine, thus materially facilitating inspection and handling of material passing through the rolls, from the feeding position of the operator at the rear of the wringer.

15 Another object of the invention resides in the provision of a quickly releasable and detachable pressure roll, which permits ready access to the material in the event the same becomes entangled in either the pressure or driven roll.

20 A still further object resides in the provision of a novel feed trough designed to allow ready feeding of the material to the rolls, either by hand, or with a stick or paddle, and at the same time prevent contact of the hand or fingers with 25 the rolls.

Incidental to the foregoing, a more specific object of the present invention is to provide a clothes wringer in which the pressure roll is carried by a quickly detachable shiftable frame 30 frictionally locked in pressure adjusted position, and both automatically and manually releasable upon creation of excessive pressure, or jamming of the rolls.

With the above and other objects in view, 35 which will appear as the description proceeds, the invention resides in the novel construction, combination, and arrangement of parts, substantially as hereinafter described, and more particularly defined by the appended claims, it being understood that such changes in the precise embodiment of the herein disclosed invention may be made as come within the scope of the claims.

In the accompanying drawings is illustrated 40 one complete example of the physical embodiment of the present invention constructed according to the best mode so far devised for the practical application of the principles thereof.

In the drawings:

50 Figure 1 is a transverse vertical section through a wringer constructed in accordance with one form of the present invention, taken on the line 1—1 of Figure 2.

Figure 2 is a vertical longitudinal fragmentary 55 section taken on the line 2—2 of Figure 1.

Figure 3 is a fragmentary detail section taken on the line 3—3 of Figure 1.

Figure 4 is a detail section taken on the line 4—4 of Figure 2.

Figure 5 is a detail section taken on the line 5—5 of Figure 2.

Referring now more particularly to the accompanying drawings, the numeral 1 designates a base bracket provided with vertical end plates 2, in which the shaft 3 of the driven roll 4 is suitably journaled. The base bracket is attached to the usual transmission housing 5, with which conventional power-driven washing machines are equipped.

Mounted upon the base bracket 1 is an inverted U-shaped frame designated generally by the numeral 6, and comprising a transverse tubular head 7, provided at its ends with depending arms 8, the lower ends of which are bifurcated at 9 to straddle the shaft 3 of the driven roll 4, 20 as best shown in Figures 1 and 2, thus permitting both oscillatory and radial shifting movement of the frame 6 with relation to the axis of the driven roll 4.

The upper edges 10 of the end plates 2 are 25 arcuate in shape with relation to the axis of the driven shaft 3, and formed upon the inner faces of the plates adjacent their front and rear ends are cams 11, which are engaged by idler rolls 12 carried by the arms 8 of the inverted U-shaped 30 frame 6, thus causing the frame to be shifted radially with relation to the axis of the driven roll 4 upon oscillation of the same either manually or automatically, as will be hereinafter described. An idler pressure roll 13 is journaled 35 in the arms 8, and in operative position normally engages the driven roll 4, the pressure between the rolls being determined by the position of the frame 6 with relation to the cams 11, it being understood that both the pressure and 40 driven rolls are formed from resilient material, such as rubber or the like.

When the frame 6 is manually shifted to operative position, as indicated in dot and dash lines in Figure 1, it will be obvious that the cams 11 45 engaged by the rollers 12 will force the pressure roll against the driven roll under a predetermined pressure. In the adjusted position of the frame, the same is locked against oscillatory movement by means of a frictional clutch 14 carried by the 50 frame 6, and comprising a manipulating handle 15 rotatably mounted upon the tubular head 7, and connected to oppositely extending rocker arms 16, the ends of which are secured to the cam heads 17, which carry the headed studs 18. 55

journaled in the depending arms 8, as best shown in Figures 2, 3, and 4. The contacting faces between the arms 8 and the cams 17 are such as to transversely shift the studs 18 upon rotation of the cam heads 17 by manipulation of the handle 15, thus causing the sides of the end plates 2 and the cams 11 to be frictionally gripped between the heads of the studs and the arms 8, which locks the frame 6 in adjusted position. 5
10 When the lever 15 is swung to its neutral position, as shown in Figure 1, the studs are released, and upon rotation of the handle in either direction locking of the clutch is effected.

When it is desired to render the wringer inoperative, the frame 6 is merely swung to its neutral vertical position, as shown in Figure 1, during which operation the rollers 12 ride up over and seat themselves in the saddles 19 carried by the end plates 2, and cause the pressure 15 roll 13 to be shifted away from the driven roll 4.

As best shown in Figures 1 and 2, a rocker plate 26, conforming in contour to one of the saddles 19, is fast to a stud 20 journaled in one of the end plates 2. Secured upon one of the studs is 20 a depending arm 21 provided with a laterally projecting plate 22 having a cam slot 23 formed therein for reception of a roller 24, fast on the shaft 25 for controlling the transmission housed in the casing 5. In vertical inoperative position 25 of the frame 6 the roller 24 is in a central position with relation to the cam slot 23, which throws the transmission into neutral, and upon oscillation of the frame in either direction, the roller 12 will engage resilient fingers 26' carried 30 by the plate 26 to rock the arm 21, and shift the transmission bar 25 to drive the roller 3 in the desired direction with relation to the position of the frame 6.

While a specific type of friction clutch and 40 transmission control has been illustrated and described, it is understood that various arrangements are contemplated within the scope of the present invention, the salient feature of which resides in the oscillatory and shifting movement of the pressure roll carrying frame to effect quick 45 release of the rolls, and positively determine the pressure between the same.

In the operation of the present invention, assuming the rolls to be in their inoperative position, as shown in the drawings, to throw the same into operation it is merely necessary to 50 manually shift the frame 6, which causes the rollers 12 to ride off of the saddles 19 and radially shift the frame 6 with relation to the axis of the driven roll 4, causing the pressure roll to engage the driven roll. The pressure between the rolls is then determined by the position of the frame 6 with relation to the cams 11 and when the desired pressure is effected, the frame is locked 55 in its adjusted position through manipulation 60 of the handle 15, which actuates the clutch 14 to frictionally bind the frame upon the end plates 2. Obviously, oscillation of the frame 6 also effects rotation of the rocker plate 26 to throw the 65 driving transmission into operative engagement with the driven roll, in the manner heretofore described.

In the event it is desired to release the rolls, a slight rotation of the handle 15 releases the 70 clutch 14, and the frame is then free to oscillate toward the saddles 19, and at the same time shift radially as the rollers ride up upon the saddle to space the rollers and throw the transmission into neutral, which renders the wringer inoperative. 75

In addition to manual release of the wringer, should articles become jammed or stuck within the rolls, creating excessive pressure, or tending to stop their rotation, the force created would be sufficient to overcome the frictional bind between the end plates 2 and the frame 6, and cause the frame to be shifted toward its vertical position, due to the direction of drive of the roll 4, which would automatically space the rolls and release the material caught therebetween, as well as causing the driving transmission to be thrown into neutral. 5
10

In addition to the foregoing, should articles become wound upon either of the rolls, the entire frame can be readily removed from the base 15 bracket by merely lifting the same upwardly when in vertical position.

While various types of feed troughs may be employed without affecting the salient features of the invention, the form of trough illustrated is 20 preferred, in that it enables the operator to readily feed material to the rolls without danger of catching the fingers or hand between the same, and at the same time permitting material to be fed to the rolls with a stick or paddle, as is frequently customary in power-driven wringers. The foregoing is accomplished by means of a trough provided with a transverse rib 27 detachably mounted upon the studs 29 carried by the end plate 2, and supported by legs 30 engaging 30 the edges of the base bracket. The trough 27 is provided with a transverse rib 31, and terminates in an upturned inner lip 32 adjacent the driven roll 4. Positioned above the rib 31, and journaled in the sides 33 of the trough, is a guard 34, preferably in the form of an idler roll. Obviously, the guard 34, in cooperation with the rib 31, forms a restriction to prevent insertion of the hand sufficiently to allow contact of the fingers with the rolls, and yet at the same time allow feeding of 40 the material to the rolls. The bottom of the trough between the rib 31 and the inner lip 32 is provided with a transverse series of openings 34 to allow drainage. 35

From the foregoing explanation, considered in connection with the accompanying drawings, it will be seen that an exceedingly simple and highly novel structure of wringer has been devised, which not only allows rapid adjustment and release of the pressure roll, but also quick detachability and complete access to material entangled in the rolls. In addition to the foregoing, due to the angle at which the rolls are set in operative position, the operator has full vision and access to material fed to the rolls from the feeding position, whereas heretofore it has been necessary for the operator to stand at the side of conventional wringers. 50
55

I claim:

1. A clothes wringer comprising a base, a driven roller journaled in said base, a frame both radially slideable and pivotally journaled directly upon said driven roll, a pressure roll journaled in said frame, means for radially shifting said frame with relation to the axis of said driven roll upon rotation of said frame, and means for locking said frame in adjusted operative position. 60

2. A clothes wringer comprising a base, a driven roll journaled in said base, a frame radially slideable and pivotally mounted upon said base with 70 relation to said driven roll, a pressure roll journaled in said frame, a manually operable cam interposed between said base and frame for radially shifting said frame with relation to the axis of said driven roll upon rotation of said 75

frame, and means for manually locking said frame in adjusted operative position.

3. A clothes wringer comprising a base, a driven roller journaled in said base, a frame radially slideable and pivotally mounted upon said base with relation to said driven roll, a pressure roll journaled in said frame about its pivotal axis, means interposed between said base and frame for radially shifting said frame with relation to the axis of said driven roll upon rotation of said frame about its pivotal axis, and manually controlled means for frictionally locking the same in adjusted position.

4. A clothes wringer for attachment to a driven washing machine provided with a wringer driving transmission comprising, a base, a driven roller

journaled in said base and operatively connected with said transmission, a frame radially slideable and pivotally mounted upon said base with relation to said driven roll, a pressure roll journaled in said frame about its pivotal axis, means interposed between said base and frame for radially shifting said frame with relation to the axis of said driven roll upon rotation of said frame, means carried by said frame for controlling said transmission upon movement of said frame, and manually operable means for frictionally locking the same in adjusted position upon said base.

EDWARD STROSCHEN.
